UNITED STATES PATENT OFFICE.

ALBERT MIRRA, OF PARIS, FRANCE.

LINKING DEVICE.

Application filed February 20, 1926, Serial No. 89,741, and in France December 1, 1925.

The present invention has for its object a new linking device which is chiefly applicable to articles of jewelry such as bracelets, necklaces or the like, but can be further utilized for all constructions which comprise assembled pieces, and which although constituted by rigid elements or units, are to possess a certain flexibility.

The linking device, the object of the invention is chiefly characterized in that it comprises strips of suitable shape which are crossed, then bent into position and soldered together, so that the whole arrangement can be pivoted without the use of slots or pins. In my said linking arrangement, the several unit elements or strips have a uniform size and shape.

Further characteristics of the invention will be set forth in the following description with reference to the appended drawings which are given by way of example.

Fig. 1 is a plan view of a unit element or shaped strip which is employed in the first embodiment of the invention, and

Fig. 2 is a section of the same on the line A—A of Fig. 1.

Fig. 3 is a view corresponding to an intermediate position during the assembling of two like elements as shown in Fig. 1, and

Fig. 4 is a section of the same on the line B—B of Fig. 3.

Fig. 5 is a plan view of a linking arrangement according to the invention in the finished state, and

Fig. 6 is a corresponding perspective view.

Figs. 7 and 8 relates to a linking device according to the invention, adapted to a jointed object.

Fig. 9 is a plan view of a portion of a suitably shaped strip corresponding to the pivot joint, as employed in a modification of the preceding device.

To carry out the linking arrangement, according to the form of construction shown in Figs. 1 to 8, I utilize elements of a single type consisting of strips which are given a special shape, for instance as shown in Fig. 1. The central part of such elements is thicker than the outer parts or wings 2, the thickness at 1 being three times the thickness at 2.

The said elements are placed together as shown in Figs. 3 and 4 and are then bent upon the lines a—a so that the wings 2 of each element will be brought down upon the

same side with reference to the central part 1, with which they now enter into contact.

Due to the amount and the disposition of the additional thickness of the central parts 1, the wings 2 of the several elements, which are superposed opposite the joint, will not afford any additional thickness at this point, and in like manner, when the said wings are brought upon the central part, their ends will also come together. If the thickness of one of the wings is taken as the unit thickness, one will obtain a uniform thickness of 4 upon the whole length of the linked device.

The amount of the rotation will depend upon the size of the cut-out parts of the elements situated at 3.

If the strips were infinitely thin, the pivoting axis of the device would obviously be situated at o, but in practice, since the strips have a certain thickness, as shown for instance in Fig. 6, when they are bent, the pivot axis is so displaced that the actual axis is above the theoretical axis by a distance depending upon the thickness of the strips.

To suitably employ my invention for the linking together of the members 4 constituting an object of any kind (Figs. 7 and 8), I provide a slot at the edges of the elements 4 in which are soldered the different links of the device according to the invention, the depth of the slot being sufficient to leave but a very slight thickness of metal above the said links, this thickness being preferably equal to the amount of the vertical displacement of the pivot centre. I thus obviate all spaces between the assembled members 4, since the pivot axes are now at the level of the outer surfaces of the said members.

Obviously, the aforesaid arrangement is susceptible of various modifications in detail, and in particular, as shown in Fig. 9, a stud may be provided at 5 for insertion into a co-operating slot at 6 which is formed in the part of the next element corresponding to the joint.

Having now described my invention, what I claim as new and desire to secure by Letters Patent is:

1. In a linking device a number of links each of which comprising a strip having its ends rounded in the shape of a circular arc and two V-shaped wings projecting from each rounded end of said strip and having less thickness than said strip, the exterior

edge of each wing on the portion adjacent to the strip being the prolongation of the circular arc of the rounded end of said strip, each wing being adapted to be engaged with 5 its two arms on either side of the two arms of the adjacent V-shaped wing of the next link, to fit into the rounded end of the strip of said next link and to be folded with its free arm lying on one face of said strip.

10. 2. In a linking device a number of links each of which comprising a strip having its ends rounded in the shape of a circular arc and two V-shape wings projecting from each rounded end of said strip and having 15 less thickness than said strip, the exterior edge of each wing on the portion adjacent to the strip being the prolongation of the circular arc of the rounded end of said strip, said two wings being adapted to be engaged 20 respectively with their two arms on either side of the two arms of the adjacent V-shaped wings of the two adjacent links, to fit into the rounded ends of the strips of said adjacent links and to be folded with 25 their two free arms lying on the same face of said strip.

3. In a linking device a number of links each of which comprising a strip having its ends rounded in the shape of a circular arc 30 and two V-shaped wings projecting from each rounded end of said strip and having less thickness than said strip, the exterior edge of each wing on the portion adjacent to the strip being the prolongation of the circular arc of the rounded end of said strip, said two wings being adapted to be engaged respectively with their two arms on either side of the two arms of the adjacent V-shaped wings of the two adjacent links, to fit into the rounded ends of the strips of said adjacent links and to be folded with 35 their two free arms lying on the same face of said strip, and having their ends secured to each other.

45. 4. In a linking device a number of links each of which comprising a strip having its ends rounded in the shape of a circular arc and two V-shaped wings projecting from each rounded end of said strip and having a 50 thickness which is the third of the thickness of said strip, the exterior edge of each wing on the portion adjacent to the strip being the prolongation of the circular arc of the rounded end of said strip, said two wings being adapted to be engaged respectively 55 with their two arms on either side of the two arms of the adjacent V-shaped wings of the two adjacent links, to fit into the rounded ends of the strips of said adjacent 60 links and to be folded with their two free arms lying on the same face of said strip.

5. In a linking device a number of links

each of which comprising a strip having its ends rounded in the shape of a circular arc 65 and two V-shaped wings having less thickness than said strip and projecting from each rounded end of said strip on only a part of said circular arc leaving a free space 70 for the rotation of the adjacent links, the exterior edge of each wing on the portion adjacent to the strip being the prolongation of the circular arc of the rounded end of said strip, said two wings being adapted to be engaged respectively with their two arms on either side of the two arms of the adjacent V-shaped wings of the two adjacent links, to fit into the rounded ends of the strips of said adjacent links and to be folded with 75 their two free arms lying on the same face of said strip.

6. In a linking device a number of links each of which comprising a strip having its ends rounded in the shape of a circular arc, two V-shaped wings projecting from each rounded end of said strip and having less thickness than said strip, the exterior edge of each wing on the portion adjacent to the strip being the prolongation of the circular arc of the rounded end of said strip, a stud 80 and a slot in each wing, each stud being adapted to engage the slot in a wing of the adjacent link, each wing being adapted to be engaged with its two arms on either side of the two arms of the adjacent V-shaped wing of the next link, to fit into the rounded end of the strip of said next link and to be folded with 85 their free arm lying on one face of said strip.

7. In a linking device a number of flat members which are to be linked together, 90 grooves on the lower face of said members, an equal number of links each of which comprising a strip having its ends rounded in the shape of a circular arc and two V-shaped wings projecting from each rounded end of 95 said strip and having less thickness than said strip, the exterior edge of each wing on the portion adjacent to the strip being the prolongation of the circular arc of the rounded end of said strip, each wing being adapted to be engaged with its two arms on either side of the two arms of the adjacent V-shaped wing of the next link, to fit into the rounded end of the strip of said next link and to be folded with 100 its free arm lying on one face of said strip, each link being inserted in the groove of one of the members to be linked, said grooves being deep enough for having the axis of rotation of the links 105 on the upper face of said flat members.

110 In testimony whereof I have signed my name to this specification.

ALBERT MIRRA.
